FACE SHIELD FOR ATTACHMENT TO HELMET

John W. Meadows, Natick, Mass., assignor to M.G.S., Inc., Framingham, Mass.

Filed May 15, 1975, Ser. No. 577,729

Term of patent 14 years

Int. Cl. D2—03

U.S. Cl. D2—233

FIG. 1

FIG. 3

FIG. 1 is a front view in elevation of a transparent face shield showing my new design;

FIG. 2 is a left-hand side view in elevation of the same face shield; and

FIG. 3 is a top plan view of the face shield.

I claim:

The ornamental design for a face shield for attachment to helmet, substantially as shown and described.
